UNITED STATES PATENT OFFICE.

ELLSWORTH B. A. ZWOYER, OF PERTH AMBOY, NEW JERSEY.

PRESS.

1,181,199.

Specification of Letters Patent.

Patented May 2, 1916.

Application filed January 27, 1916. Serial No. 74,581.

To all whom it may concern:

Be it known that I, ELLSWORTH B. A. ZWOYER, a citizen of the United States, and resident of Perth Amboy, county of Middlesex, State of New Jersey, have invented a certain new and useful Press, of which the following is a specification.

This invention relates to improvements in presses for making briquets or similar articles or for crushing or embossing, and has for its objects: First: To bring certain parts of the two rolls into operative position with facility, even when the press is in operation and under load. Second: To permit readjustment for wear of the rolls and at the same time keep certain parts of the two rolls in operative position. Third: To facilitate adjustment of the rolls in mutual relation and resist strains on the bearings. Fourth: To render the press interchangeable so that it may be used as a right or left hand press.

These and further objects will more fully appear from the following specification and accompanying drawings, considered together or separately.

In the drawings; Figure 1 is a plan view of a press for making briquets embodying my invention; Fig. 2 is a side view thereof; Fig. 3 is a sectional view on the line 3-3 of Fig. 1; Fig. 4 is a sectional view on the line 4 of Fig. 1; Fig. 5 is a diagrammatic plan view of a press when used as a right handed press; Fig. 6 is a similar view of the same press when used as a left handed press; Figs. 7, 8, 9 and 10 are diagrammatic views of certain parts of a press for making briquets showing adjustment of the rolls for wear and wherein the pockets are kept in coincidence after such adjustment.

In all views like parts are designated by the same reference characters.

The press illustrated in Figs. 1 to 10 of the drawings comprises a base 1 having a bed 2 thereon. On this bed are suitable ways 3, 3. Mounted upon these ways is a subframe 4. This subframe is shown in Fig. 1 preferably as continuous. It may be made of one or more pieces. The ends of the frame inclose the rolls. Mounted upon the subframe are moving bearing boxes 5, 5 and fixed bearing boxes 24, 24, see Fig. 4. A roll shaft 6 is carried in the bearings 5. A second roll shaft 7 is carried in the bearings 24. Rolls 8 are mounted upon the shaft 6 and rolls 9 are mounted upon the shaft 7.

Carried by the subframe and located above the rolls is a hopper 10. A gear 11 is mounted upon the shaft 6 and a similar gear 12 is mounted upon the shaft 7. A drive shaft 13 is mounted in suitable bearings on the base and a jack shaft 14 is mounted in suitable bearings also upon the base and parallel to the drive shaft. A pinion 15 is carried upon the drive shaft 13 and meshes with the gear 11, and a second pinion 16 is mounted upon the jack shaft 14 and meshes with the gear 12. A suitable drive pulley 17 is mounted upon the drive shaft 13. Suitable matching gears 21 are carried upon the two shafts 13 and 14 and interengage. The moving bearing boxes 5, 5 are suitably adjusted by means of screws 18, see Fig. 5. These screws are provided with a suitable worm gear 19 actuated by a shaft which is turned by means of a crank 20. Suitable screws 22 carried by the bed 2 are adapted to move the subframe in one direction and similar screws 23 also carried by the bed engaging with the subframe are adapted to move the latter in the opposite direction. The rolls are provided with suitable pockets 25, of such a shape as to make a briquet of a desired size and configuration.

With the parts assembled as shown, power being applied to the pulley 17 it will rotate the drive shaft 13. The jack shaft 14 will, through the agency of the matching gears 21, also be rotated in the opposite direction at the same speed. The pinions 15 and 16 will rotate the gears 11 and 12 respectively, also at the same speed, and these gears will rotate the roll shafts 6 and 7 and with them the rolls 8 and 9. In the course of time the faces of the rolls will wear so that there is a separating interval between them, as shown in Fig. 8. When this occurs imperfect briquets will be produced. It is desirable that the rolls be adjusted to take up this wear so that they will be placed in a position, shown in Fig. 4, in which the faces of the rolls will be close together. The adjustment for wear is made by the moving of the box 5 in a direction toward the box 24. This is obtained by rotating the crank 20 which will turn through its shaft, the worm gear 19, the two screws 18, 18 engaging with the two boxes 5, 5. This will simultaneously move the two boxes in the direction toward the shaft 7. This movement will continue until the two shafts are in proper relative position to make up

for the loss through wear on the rolls. As the boxes 5, 5 are moved and with them the shaft 6, the gear 11, mounted on the shaft 6, will rotate upon the pinion 15, the latter being stationary owing to the engagement of the matching gears 21 with each other. Therefore, as the shaft 6 is moved toward the shaft 7, the gear 11 will rotate through its engagement with the pinion 15, as described, thus rotating the roll 8 so that when the rolls are brought into proper relative position to take up the wear the pockets will not be in coincidence. This situation is shown in Fig. 9. In order to bring the pockets into coincidence the subframe is moved to the left. This is attained by first unscrewing the screws 22 and screwing up the screws 23 to the desired amount, moving the subframe in the direction of the horizontal arrow *a* in Fig. 10. While this is being done the gears 11 and 12 will rotate upon the fixed pinions 15, 16, both in the same direction, as shown by the curved arrows *b*, *b* in Fig. 10. The result will be that both rolls turning in the same direction, their passing faces will turn in opposite direction. This movement of the subframe will be continued until the pockets are in exact coincidence. When this is attained the screws 22 can be screwed into contact with the frame and the lock nuts upon these screws can be tightened to prevent any further movement.

The adjustment of the boxes in relation to one another may be easily attained by simply rotating the crank 20. Any slight adjustment for wear may therefore be taken up without stopping the press. The subframe encircling the two rolls as shown produces a very strong construction and will resist strains, localizing all stresses due to the material passing between the rolls.

The press has the further advantage that it may be used either as a right handed or left handed press. The manner in which this is done is diagrammatically illustrated in Figs. 5 and 6. If it is desired to change the right-handed press (Fig. 5) into a left-handed press (Fig. 6), without changing the position of the base 1 and without changing the end upon which the drive pulley is, it is merely necessary to reverse the position of the subframe 4 which will reverse the position of the rolls 8 and 9. The drive shaft and jack shaft are interchanged. When thus interchanged the parts will be in the position shown in Fig. 6. The roll 8 will be driven through the agency of the drive shaft 13 and the roll 9 will be driven through the agency of the jack shaft 14 as before, but the parts will be reversed as shown.

A press made according to my invention may be so adjusted that the rolls will perfectly match while the press is at rest or

running, without material passing through. When material is in the press and between the rolls, one of them may have a tendency to move upward in its bearings, thus placing the pockets out of alignment. This may particularly occur after the bearings wear. When this happens the pockets can be very readily restored to alignment by loosening one set of horizontal screws 22 or 23 and tightening the other set, as hereinbefore described. This may be done while the press is in operation even when running under load. It will, therefore, be seen that a very desirable feature of the invention is that the rolls may be adjusted to bring the pockets into coincidence irrespective of the wear on the latter. This feature is useful when the press is first built. It is a very difficult matter to properly key a roll to a shaft in relation to the matching gear so that the pockets are in exact alignment.

According to this invention no care at all is to be taken in keying the roll to the shaft for the purpose of securing alignment of the pockets. The alignment may be obtained afterward in the manner hereinbefore described.

While I have described my invention particularly as applied to a press for making briquets, it is to be understood that the invention may not be so limited as the rolls may be used for other purposes.

In accordance with the provisions of the patent statutes, I have described the principle of my invention, together with the apparatus which I now consider to represent the best embodiment thereof; but I desire to have it understood that the apparatus shown is merely illustrative and that the invention may be carried out in other ways.

Having now described my invention, what I claim as new and desire to secure by Letters Patent, is:

1. A press having a pair of pocketed rolls, means for rotating the rolls in the same direction to bring the pockets into coincidence.

2. A press having a pair of pocketed rolls, bearings for the rolls, driving gears for the rolls, and means for moving both bearings in the same direction in order to bring the pockets into coincidence.

3. A press comprising a pair of pocketed rolls, bearings for the same, gears rotating the rolls, drive shafts, gears carried by the drive shafts engaging with the roll gears, and means for moving both shafts in the same direction to bring the pockets into coincidence.

4. A press having a base, a bed thereon, a subframe on said bed, a pair of driving shafts, pinions thereon, shaft bearings carried by the subframe, a pair of rolls mounted in the bearings, gears carried by

the roll shafts engaging with the aforesaid pinions, and means for moving the subframe in relation to the base.

5. A press having a pair of pocketed rolls, means for moving the rolls in relation to one another to provide for adjustment for wear, and means for rotating the rolls in the same direction to bring the pockets into coincidence after such adjustment.

10 6. A press having a pair of pocketed rolls, bearings for the rolls, driving gears for the rolls, means for moving one bearing toward or away from the other bearing to adjust for wear, and means for moving both bearings in the same direction in order to bring the pockets into coincidence after such adjustment.

20 7. A press comprising a pair of pocketed rolls, bearings for the same, gears rotating the rolls, drive shafts, gears carried by the drive shafts engaging with the roll gears, means for moving one roll in relation to the other to adjust for wear, and means for moving both shafts in the same direction to bring the pockets into coincidence.

25 8. A press comprising a base having ways thereon, a subframe mounted upon said ways, a pair of rolls mounted within the subframe, said subframe encircling the rolls.

30 9. A press having a base, a bed thereon, a subframe on said bed, a pair of driving shafts, pinions thereon, shaft bearings carried by the subframe, a pair of rolls mounted in the bearings, gears carried by the roll shafts engaging with the aforesaid pinions, means for moving the bearings in relation to one another, and means for moving the subframe in relation to the base.

35 10. A press comprising a base having ways thereon, a removable drive shaft and removable jack shaft thereon, each of said shafts carrying a pinion, a subframe mounted upon the aforesaid ways and carrying two roll shafts, gears carried by the roll shafts, one of said gears extending on one side of the subframe and the other gear upon the other side of the subframe, whereby said subframe may be reversed upon the ways, and said drive shaft and counter shaft

40 45 50 may be interchanged so that a right-handed press will be converted into a left-handed press, or vice versa.

11. A press having a pair of rolls, means for rotating the rolls in the same direction to bring certain parts of the two rolls into operative position.

12. A press having a pair of rolls, bearings for the rolls, driving gears for the rolls, and means for moving both bearings in the same direction in order to bring certain parts of the two rolls into operative position.

13. A press having a pair of rolls, bearings for the rolls, driving gears for the rolls, means for moving both bearings in the same direction to bodily move both rolls in the same direction, thereby rotating both rolls in the same direction and moving certain parts of the rolls into operative position.

70

14. A press comprising a pair of rolls, bearings for the rolls, gears rotating the rolls, driving shafts, gears carried by the driving shafts engaging with the roll gears, and means for moving both shafts in the same direction to bring certain parts of the two rolls into operative position.

15. A press having a pair of rolls, means for moving the rolls in relation to one another to provide for adjustment for wear, and means for rotating the rolls in the same direction to bring certain parts of the two rolls into operative position after such adjustment.

80

16. A press having a fixed frame, a pair of gears carried thereby, a movable subframe carried by the fixed frame, bearings carried by the subframe and movable in relation thereto, rolls carried by the bearings and having gears which engage with the gears on the fixed frame, the line of movement on the subframe in relation to the fixed frame being substantially parallel to the plane of the axes of the gears on the fixed frame.

95

17. A press having a fixed frame, a pair of spur pinions carried thereby, a movable subframe carried by the fixed frame, bearings carried by the subframe and movable in relation thereto, rolls carried by the bearings and having spur gears which engage with the pinions, the line of movement of the subframe in relation to the fixed frame being substantially parallel to the plane of the axes of the pinions.
